SLOW SPEED TIME MARKER

Wayne A. Alford, Denver, Colo., assignor to Hathaway Instrument Company, Denver, Colo.

Application September 15, 1951, Serial No. 246,841

3 Claims. (Cl. 346—107)

1

The present invention relates to a time marking device for oscilloscope, and more particularly to an improved slow speed time marker.

When oscilloscope recording is done at slow speeds in a photo-sensitive record material moving at a speed of a few inches per second or slower, it frequently is desirable to have time coordinate lines on the chart paper at one second and at 10-second intervals. To obtain a record of proper accuracy and appearance, it is desirable to have these time coordinate lines of proper width and intensity.

Heretofore, time coordinate lines have been obtained by the use of an arrangement employing an electric switch which periodically illuminated a filament type lamp bulb. Light from this bulb was reflected to the recording charts material by means of a mirror and lens system. The time required for warming up the light bulb filament to incandescence and the time required for incandescence to die out represented a definite time interval, making it impossible to produce a narrow time line. The electric switch in such arrangement generally was driven by a motor driven cam so that a variable time delay could be introduced unknown to the operator, therefore, producing inaccurate time coordinate lines.

In accordance with the present invention it is proposed to overcome the disadvantages of the prior art by an arrangement which will produce narrower time coordinate lines and in which no error can occur due to mechanical and electrical variations. This is accomplished by the use of a continuously illuminated lamp and a shutter arrangement so that light is emitted periodically.

It is therefore, an object of the present invention to provide a coordinate time marker for photo-sensitive oscilloscope recording material which provides accuracy and time coordinate lines of the desired width.

A still further object of the present invention is to provide particularly for slowly moving record materials in an oscilloscope, a slow speed time coordinate marker of improved construction.

Other and further objects of the present invention subsequently will become apparent by reference to the following description taken in conjunction with the accompanying drawing, wherein:

Figure 1 is a side view of a slow speed time coordinate marker embodying the principles of the present invention; and

Figure 2 is an enlarged detailed view of a portion of the mechanism shown in Figure 1.

Referring to the drawing it will be seen that 55 by an auxiliary shaft 44. The gear 43 is con-

2

there has been shown a supporting panel 11 which may be a portion of the oscilloscope case or which may be a separate panel adapted to be mounted on the oscilloscope case where an arrangement such as is to be described, is used as an accessory. The panel 11 is provided with a pair of binding posts 12 for supplying current to a synchronous electric motor, and another pair of binding posts 13 for supplying externally controlled current to the filament of an electric incandescent bulb. The front of the panel 11 carries a plate 14 secured by suitable screws 15 to an end plate 16, which supports a cylindrical tube 17 secured thereto by suitable fastening means which might include a plurality of screws 18. The cylindrical tube 17 is fastened by suitable means, such as screws 19 to another end plate 21. The end plate 21 is carried by a plurality of posts 22 which supports the frame of a self-starting synchronous 10 alternating current motor 23.

The cylinder 17 at an intermediate point, is provided with a longitudinal slot 20, the opening of which may be controlled by a shield 24 retained in proper adjusted position by a screw 25. Light 15 emitted from the slot adjacent to shield 24 impinges upon a mirror 26 adjustably positioned between a pair of support arms 27 secured to one side of the cylinder 17.

The end wall and support 16 of the cylinder 17 is provided with a bearing support or sleeve extension 28 for carrying a rod or tube 29. The sleeve 28 is provided with a slot 31 which is engaged by a pin 32 carried by the rod 29. The rod 29 which extends to the front of the panel 11 30 is provided with a knob 33 so that the rod 29 may be reciprocated by an amount determined by the pin 32 operating within the slot 31 of the bearing support 28. At the other end of the rod 29, there is located a cylindrical support 34 35 which carries a socket 35 for an incandescent bulb 36. The bulb 36 serves as the light source which is emitted periodically to impinge upon the mirror 26 from which it is reflected to the photo-sensitive record material of the oscilloscope. 40

The lamp 36 is surrounded by a shutter comprising two concentric cylinders shown in detail in Figure 2. The synchronous electric motor 23 has a shaft 37 which carries a gear 38 formed at one end of a sleeve 39. The sleeve 39 at its outer end carries a cylindrical support element 41 upon which is secured a cylinder 42 having a single longitudinal slot therein.

The gear 38 engages a reduction gear 43 carried 50 by an auxiliary shaft 44. The gear 43 is con-

nected to a smaller gear 46 which drives a larger gear 47. The gear 47 is carried by a sleeve 48 extending through the end wall 21 of the cylinder 17. On the other end of the sleeve 48 there is mounted a cylindrical support 51 which carries a slotted cylinder 52 which is of larger diameter than the cylinder 42. In order to prevent light from leaking along the sleeve 48 a suitable felt washer 53 is retained in position by a collar 54.

The manner in which the apparatus operates will become more apparent by referring to a particular embodiment wherein the synchronous motor 23 had a speed of 60 R. P. M. for its shaft 31. The inner shutter and cylinder 42 having a single slot therein, therefore, rotated at 60 R. P. M. The speed of the outer cylinder 52 was reduced to 6 R. P. M. The outer cylinder 52 in this particular embodiment was provided with 9 slots 55 and one slot 56. The slots 55 and 56 were disposed at equal angles about the circumference of the cylinder 52. The inner cylinder 42 has a single slot of substantially the same width and length as the slot 56. With the lamp in the position shown in Figure 1, light will be transmitted through all of the slots 55 and 56 to the mirror 26 so that a flash of light is emitted once every second. If the lamp 36 is now moved toward the right, a distance determined by the length of the slot 31 in the sleeve 28, the filament of the lamp will be aligned with the outer portion of a slot 56 and no light will be transmitted through the slot 55. In this case, light will be transmitted to the mirror 26 once every 10 seconds. Thus, by mere actuation of the knob 33 the lamp 36 may be withdrawn to provide a greater time interval between the flashes of light which produce the time markers on the oscillograph records. In order that the motor 23 might be supported with proper rigidity there is provided a pin 57 which fits into a suitable support.

While, for the purpose of illustrating and describing the present invention a preferred embodiment has been shown in the drawing, it is to be understood that the invention is not to be limited thereby since such variations are contemplated as may be commensurate with the spirit and scope of the invention set forth in the accompanying claims.

I claim:

1. A slow speed time coordinate marker for an oscillograph comprising a synchronous alternating current motor, two coaxially arranged longitudinally slotted cylinders, gear means interposed between said cylinders and said motor for

rotating said cylinders in the same directions at different speeds, one of said cylinders having a larger number of slots than the other cylinder and certain of said slots being shorter than the others, at least one of said slots being as long as the slot in the other cylinder, a source of illumination coaxially located within said cylinders, and a third longitudinally slotted stationary cylinder surrounding said former cylinders having an adjustable shield for controlling the light emitted therefrom.

2. A time coordinate marker for an oscillograph comprising a longitudinally slotted cylinder mounted for rotation about its axis, a second longitudinally slotted cylinder coaxially surrounding said first cylinder and mounted for rotation about its axis, said second cylinder having a plurality of slots shorter than the slot in said first cylinder and at least one slot as long as the slot in said first cylinder, a source of illumination coaxially located within said cylinders and mounted for limited reciprocable axial movement, and a third longitudinally slotted cylinder surrounding said former cylinders having an adjustable shield for controlling the time during which light is emitted therefrom.

3. A time coordinate marker for an oscillograph comprising a longitudinally slotted cylinder mounted for rotation about its axis, a second longitudinally slotted cylinder coaxially surrounding said first cylinder and mounted for rotation about its axis, means for driving said cylinders at different constant speeds, said second cylinder having a plurality of slots shorter than the slots in said first cylinder and at least one slot as long as the slots in said first cylinder, a source of illumination coaxially located within said cylinders and mounted for limited reciprocable movement to determine whether or not light shall be transmitted through said shorter slots, and a third slotted cylinder surrounding said former cylinders having an adjustable member on said cylinder for controlling the effective aperture of the slot of said cylinder.
